The ornamental design for a three-dimensional product display board, as shown and described.

DESCRIPTION

FIG. 1 is a top, front, and right side perspective view of a three-dimensional product display board showing our new design, the broken-line disclosure of a number of products is shown for illustrative purposes only and forms no part of the claimed design;

FIG. 2 is a top plan view thereof;

FIG. 3 is a front elevational view thereof;

FIG. 4 is a right side elevational view thereof, the left side being a mirror image of that shown;

FIG. 5 is a rear elevational view thereof; and,

FIG. 6 is a bottom plan view thereof.
